A. HOFFER

LIFTING TOOL

Filed May 23, 1923

INVENTOR
Alfred Hoffer

BY
Frank Kaiser
ATTORNEY

UNITED STATES PATENT OFFICE.

ALFRED HOFFER, OF ROCHESTER, NEW YORK.

LIFTING TOOL.

Application filed May 23, 1923. Serial No. 640,973.

To all whom it may concern:

Be it known that I, ALFRED HOFFER, a citizen of the United States, residing at Rochester, in the county of Monroe and State 5 of New York, have invented certain new and useful Improvements in Lifting Tools, of which the following is a specification.

The object of this invention is to provide a tool with which concrete blocks or any 10 other similarly shaped building blocks may be conveniently and readily lifted and properly placed in erecting a wall.

This and other objects of this invention will be fully illustrated in the drawing, described in the specification and pointed out in the claims at the end thereof.

In the accompanying drawing:

Figure 1 is a front elevation of the lifting tool as it will appear when attached to a 20 concrete block for the purpose of lifting the block, the block being illustrated in section.

Figure 2 is a top plan view of the lifting tool and the concrete block to which the tool is attached, the concrete block being partly 25 broken away.

Figure 3 is a vertical sectional view of one of the handles of the tool, the section being taken on the line 3^x—3^x of Figure 1.

Figure 4 is a horizontal sectional view 30 taken on the line 4^x—4^x of Figure 1 illustrating in a top plan view the inner ends of the clamping or gripping levers of the lifting tool.

Figure 5 is a vertical sectional view 35 through the adjusting mechanism for operating the clamping levers of the lifting tool.

Figure 6 is a vertical sectional view 40 through one of the gripping shoes provided at the outer ends of each of the clamping or gripping levers.

In the several figures of the drawing like reference numerals indicate like parts.

In building walls with concrete blocks it 45 is very difficult to lift and properly place each of the blocks because these blocks are very heavy and very hard to get hold of. The lifting tool forming the subject matter of my present invention will make the handling of such concrete blocks considerably 50 easier in that when attached to the block it provides a handle for the block by means of which two men or even one man is able to lift and place the heavy concrete block on the wall without any great exertion.

As illustrated in the drawing, the lifting tool comprises the horizontal bar 1 having the handles 2 and 3 formed at each end thereof. Besides the handles the horizontal bar is provided with a pair of feet 4 and 5 60 that form suitable supports for the lifting tool and serve to align the horizontal bar with relation to the top of the block to which the lifting tool is to be attached. The horizontal bar, its handles and supporting feet 65 are preferably cast of malleable iron and the top of the bar and its handles are partially channeled to keep the weight of the lifting tool at a minimum without decreasing the strength or stiffness thereof. At the outer 70 end of the handles 2 and 3 a depending projection is formed against which the hand rests when pulling the handle to one side to prevent the hands from slipping off the end of the handles.

The supporting feet 4 and 5 as illustrated in Figure 3 are each provided with a pair of angularly projecting flanges 6 and 7 which form a wide base for the lifting tool to rest on and hold the tool in proper alignment for the gripping or clamping levers to grip the concrete block as will presently be described. At 8 and 9 the horizontal bar 1 is slotted to receive the clamping levers 10 and 11. These clamping levers are angular 80 in outline and are pivoted in the slotted portions 8 and 9 of the horizontal bar on the pivot pins 12 and 13 that pass through the horizontal bar and bridge the slotted portion thereof. A head formed on one end of 90 these pivot pins and a cotter pin projecting through the other end of the pivot pins hold these pivot pins in place on the horizontal bar.

To the lower end of each of the angular 95 clamping levers are pivoted the gripping or clamping shoes 14 and 15 respectively. These gripping shoes are made with serrations 16 on the gripping face. On the back of the shoes are provided two lugs. The 100 shoe is slotted between the lugs. Suitable bearings are provided in the lugs for the pivot pin carried on the end of the gripping levers so that the shoe can swing thereon. A flat spring 18 is fastened to the back 105 of the shoe and exerts a pressure against the rounded end of the gripping levers. The shoes are thus held against easy rotation and this serves to keep the shoes somewhere near the proper position for gripping from 110 which they will be forced into their final gripping position when the gripping levers

force the shoes against the inner walls of the concrete block and align themselves with the wall thereof.

The inner ends of the angular gripping levers 10 and 11 are flattened out and overlap each other. The flattened end of the lever 11 overlaps the flattened end of the lever 10. In these flattened ends of the levers 10 and 11 are provided elongated holes 10 through which the clamping bolt 19 passes. This clamping bolt projects up through a suitable hole in the horizontal bar 1 and has a clamping nut 20 threaded to the lower end thereof on the under side of the bar 1. On the upper end of the clamping bolt 19 is formed an eye 21 carrying the stud 22. A cam lever 23 is pivoted on the stud 22 and the cam formed on this lever is adapted to rest on top of the flattened end 20 of the gripping lever 11 on either side of the elongated hole 30 provided in this end of the lever.

An expansion spring 24 surrounds the clamping bolt 19 and is interposed between the horizontal bar 1 and the under side of the flattened end of the gripping lever 10. This spring normally forces the flattened ends of both of the gripping levers upwardly so that the flattened end of the gripping lever 11 is forced against the periphery of the cam of the cam lever 23.

The cam surface of the cam lever 23 is eccentric to the pivot of the cam lever and on swinging the lever from its dotted line position illustrated in Figure 1 to the full line position thereof the inner flattened ends of the gripping levers 10 and 11 are forced down against the pressure of the spring 24 and at the same time the lower ends of these levers with its gripping shoes 14 and 15 are forced outwardly against the end walls of the concrete block. This grips the concrete block from the inside and rigidly clamps the lifting tool thereto so that the block can be lifted by means of the handles 2 and 3 of the lifting tool.

In fastening the lifting tool to a concrete block the tool is placed in the middle of the top of the concrete block so that its supporting legs support the horizontal bar on top of the concrete block. When this is done the cam lever is swung from the dotted line position to the full line position as illustrated in Figure 1 with the result that the gripping shoes are forced outwardly against the end walls of the concrete block. The lifting tool fastened to the block in this manner provides two overhanging handles on the block by means of which one or two workmen can handle the block in a much more convenient manner than is possible without this lifting tool.

The gripping mechanism is adjustable to engage larger or smaller concrete blocks having larger or smaller openings in the

center thereof. This is done by turning the clamping nut 20 in or out on the end of the clamping bolt so as to draw the flattened ends of the gripping lever and with it the cam lever 23 down toward the horizontal bar or allow them to swing farther away from it. In this way the initial position of the lower ends of the gripping levers with their gripping shoes may be varied to engage into a smaller or larger opening of a concrete block for the purpose of gripping the end walls thereof as above pointed out.

I claim:

1. A lifting tool for building blocks having an open center, comprising a handle, a pair of gripping levers pivoted on said handle and having the lower ends thereof extending down into the block the upper ends of said lever overlapping each other, means for swinging the overlapping ends of said levers at the bottom and forcing them into contact with the inner surfaces of the end wall of the blocks.

2. A lifting tool for building blocks having an open center, comprising a handle, a pair of gripping levers pivoted on said handle and extending down into the block, means for spreading said levers at the bottom and forcing them into contact with the inner surfaces of the end wall of the blocks, shoes on the lower ends of said levers.

3. A lifting tool for building blocks having an open center, comprising a handle, a pair of gripping levers pivoted on said handle and having the lower ends thereof extending down into the block the upper ends of said lever overlapping each other, means for swinging the overlapping ends of said levers at the bottom and forcing them into contact with the inner surfaces of the end wall of the blocks, said means being adjustable to increase or decrease the swinging of said gripping levers.

4. A lifting tool for building blocks having an open center comprising a handle having slots therein, a pair of gripping levers mounted to swing in said slots with the upper ends overlapping each other and the lower ends extending down into the block, means located at the upper end of said levers for rocking said levers and forcing the lower ends thereof into contact with the inner surfaces of the end wall of the blocks.

5. In a lifting tool for building blocks, the combination of a bar, handles formed on the end of said bar, said bar being slotted at intermediate points thereof, gripping levers mounted to swing in the slotted portions of said bar, said gripping levers having gripping shoes pivoted on the outer ends thereof, a friction spring carried by each of said gripping shoes and adapted to engage the ends of said gripping levers to hold said gripping shoes in a predetermined position on the end of said gripping levers, the inner

ends of said gripping levers overlapping each other, said overlapping inner ends of said gripping levers having elongated holes provided therein, a clamping bolt projecting up through a hole in the middle of said bar and passing through the elongated openings in the overlapping ends of said gripping levers, an eye formed on the upper end of said clamping bolt, a pivot pin carried in 10 said eye, a cam mounted to swing on said pivot pin, the periphery of said cam being adapted to rest on the upper one of the overlapping ends of said gripping levers, an ex- pansion spring interposed between said bar and the overlapping ends of said gripping levers to normally hold said overlapping ends in contact with the periphery of said cam, an adjusting nut threaded to the lower end of said clamping bolt said adjusting nut being adapted to adjust the initial position 20 of said gripping shoes by lengthening or shortening the length of the clamping bolt that projects above said bar.

In testimony whereof I affix my signature.

ALFRED HOFFER.
